UNITED STATES PATENT OFFICE

2,607,958

FIBER DOFFING DEVICE

Ralph A. Rusca and Ray C. Young, New Orleans,
La., assignors to the United States of America
as represented by the Secretary of Agriculture

Application May 16, 1950, Serial No. 162,380

1 Claim. (Cl. 19—67)

(Granted under the act of March 3, 1883, as
amended April 30, 1928; 370 O. G. 757)

1

The invention herein described may be manufactured and used by or for the Government of the United States of America for governmental purposes throughout the world without the payment to us of any royalty thereon.

This invention relates to a device for doffing cotton or other fibers from a rotatable processing cylinder such as a toothed cylinder, spiked drum, a smooth or fluted roll, etc., particularly to such a device for doffing cotton from a toothed cylinder of the cotton-working machine of U. S. Patent No. 2,365,793, and has among its objects the provision of such a doffing device which is long-wearing. Other objects will be apparent from the description of the invention.

The cotton working machine of Patent No. 2,365,793 is a fiber processing machine having a number of rotatable processing toothed cylinders, each of which collects fibers on its periphery during their processing. In this machine the fibers are doffed from the cylinder by rotating brush-cylinders (for example, those characterized by the numerals 30 and 31 in the patent). The brushes on these cylinders are not long wearing, however, due to destruction of the bristles by contact with the toothed cylinders. In the instant invention an improved doffer for removing the fibers from the processing toothed cylinder of the afore-mentioned cotton working machine is provided.

In general, according to the present invention, the doffer comprises a rotatable doffer cylinder having its axis parallel to that of the processing cylinder and having, also, radially extending doffer teeth on its periphery which run closely adjacent to, but out of contact with, the periphery of the processing cylinder. The forward edge of each of these doffer teeth is constructed at such an angle to the radius of the doffer cylinder that the teeth collect the fibers from the periphery of the processing cylinder as they run closely adjacent thereto, and the fibers are expelled therefrom by centrifugal force within a complete revolution of the doffer cylinder.

Due to the fact that the doffer teeth do not contact the processing cylinder the doffing device is subject to little wear.

ence is made to the accompanying drawing in which:

Fig. 1 is a side elevation of a portion of a cotton working machine of the type shown in Fig. 1 of U. S. Patent No. 2,365,793, with parts broken away for purpose of illustration;

Fig. 2 is a partial section along the line 2—2 of Fig. 1, part being a top plan view of a processing cylinder and doffer cylinder;

Fig. 3 is a detail view showing the doffer teeth;

Fig. 4 is a schematic plan view of a second modification showing a processing cylinder and a doffer cylinder;

Fig. 5 is a schematic plan view of a third modification showing a processing cylinder and a doffer cylinder;

Fig. 6 is a schematic plan view of a fourth modification showing a processing cylinder and a doffer cylinder;

Fig. 7 is a vertical section of a portion of a roller gin apparatus embodying the doffer; and

Fig. 8 is a vertical section illustrating a cage condenser embodying the doffer.

Referring with more particularity to Figures 1-3 of the drawing, there are shown processing toothed-cylinders 11 and 12 and endless feedbelt 13 which corresponds respectively to cylinders 18 and 19 and belt 36 of the machine of Patent No. 2,365,793. Any number of such processing cylinders may be used although only two are shown. Since these cylinders and their related parts are similar, only one and its related parts, will be described in detail.

As the processing cylinder 12 continuously picks a thin layer from the mass of cotton, the picked lint is continuously removed from this cylinder by doffer cylinder 14 rotatably mounted with its axis of rotation parallel to the axis of rotation of the processing cylinder. Rotation of the doffer cylinder may be accomplished by any suitable means, such as a belt and drive pulley similar to that shown in the patent for rotating the brush-cylinders. Cylinder 14 comprises essentially a shaft 15 on which are mounted a number of discs 16, each of which is provided with peripheral V-shaped doffer teeth 17, these discs being axially spaced by spacing discs 18. The parts are held assembled by clamping nut 19.

The doffer teeth 17, which extend radially on the periphery of the doffer cylinder, run closely

adjacent to, but out of contact with, the periphery of the processing cylinder 12. The forward edge 20 of each of the doffer teeth 17 is constructed at such an angle X to the radius of the doffer cylinder 14 that the teeth collect the fibers from the periphery of the processing cylinder as they run closely adjacent thereto. The shape of the doffer teeth is important. For cotton fibers each tooth should be rearwardly inclined from the direction of rotation at the angle X from about 5° to 45°, the angle depending on the rotational speed and diameter of the doffer cylinder. Thus, for a 7½ inch diameter cylinder rotating at 800 R. P. M., a 10° angle has been found to give best results.

After the teeth collect the fibers from the processing cylinder, the fibers are expelled by centrifugal force within a complete revolution of the doffer cylinder, generally in about a one-quarter revolution, into a duct 21 and thereafter conveyed by air currents, created by a suction fan (not shown) to any subsequent process. Air from the atmosphere enters through inlet port 22.

In the embodiments illustrated in Figs. 1-3, it is essential that the processing cylinder and doffer cylinder rotate in opposite directions and that the peripheral speed of the doffer cylinder exceed that of the processing cylinder, preferably with the doffer cylinder peripheral speed being about twice that of the processing cylinder.

Discs 16 may be constructed either of non-yieldable or of yieldable materials. For cotton fibers we have found that metal discs are preferable, but in applications on other machines and on other materials, leather, canvas, rubber and similar materials can be employed. The hard disc has the advantage of long life with a minimum of wear while the soft disc is less apt to damage delicate fibers.

Similarly, the spacing discs 18 may be constructed either of hard or soft materials. We have found the former to be superior for most uses because of its improved wearing qualities; however, the apparatus will work equally well with yieldable spacing discs. The discs 18 should preferably be of a diameter large enough to be within $\frac{1}{16}$ inch of the root of the teeth 17 on discs 16.

In the embodiment, shown in Fig. 4, the discs 25 of doffer cylinder 26 are inclined by suitable means to produce a wobble motion of the teeth when in operation and thereby cause the doffer teeth to sweep back and forth across the processing cylinder 27. For doffing cotton fibers, the teeth of the doffer should clear the teeth of the processing cylinder by approximately $\frac{1}{64}$ inch; however, larger clearances can be used if desired. This method of wobbling the discs 25 works well with the processing cylinder teeth rotating in a fixed plane.

In the embodiment shown in Fig. 5 both the processing cylinder discs 30 of processing cylinder 31 and the discs 32 of doffer cylinder 33 are inclined by suitable means to produce a wobbling motion of the teeth carried thereby. This method of wobbling the discs of both the processing and doffer cylinders is employed in the well-known art of reginning cotton lint.

Figure 6 illustrates an embodiment which has been found to work satisfactorily, and is preferred for use when very short fibers are to be doffed. The discs 35 of doffer cylinder 36 are intermeshed with the processing cylinder discs 37 of processing cylinder 38 to any desired depth. For cotton fibers the tips of the doffer teeth should mesh to the root of the processing cylinder teeth. 75

Figure 7 illustrates application of the doffer to a conventional roller type gin used for ginning long-staple seed cottons. Seed cotton 40 is fed into a hopper 41 where it is agitated into contact with roller 42. Roller 42 is covered with walrus hide 43, or hydraulic packing material, which has the property of causing cotton fibers to adhere to its surface. Fixed knife 44 and movable knife 45 co-act to shear off the cotton seed, thereby permitting the fibers to be carried around on roller 42 in the direction indicated. Seeds 46 gravitate out of the gin on chute 47. Knife 45 is caused to move in a vertical plane by use of an eccentric 48 and push bar 49, or by other suitable means. 10 Doffer cylinder 50 rotatably mounted in pairs of bearings (not shown) and rotated by any suitable means in the direction shown, removes the fibers from roller 42.

The present invention has the advantage of 20 positively removing the fibers from the walrus hide roller, which prevents the roller from carrying around the fibers and causing chokages at the seed chute or the knife blades. Heretofore, roller 42 was doffed by rubber flaps fastened to the surface of a doffing roll, or occasionally by the use of air suction at some point on roller 42. Neither of these methods is positive in action, and neither prevents fibers from accumulating on the surface of the roll and causing subsequent stoppage of 30 the gin.

A further application of the present invention is for doffing fibers from conventional textile cage condensers. Figure 8, for example, shows an embodiment wherein our invention is used in standard suction type cage condenser. Cotton or other textile fibers 55 are conveyed by air onto a perforated metal or open mesh screen drum 56. Drum 56 is rotatably mounted in pairs of bearings (not shown) and is positively driven in the direction indicated by any suitable means. An airtight metal enclosure 57 directs the fibers to the drum. The fiber conveying air exhausts through the perforations of drum 56, and thence through the ends of the drum, through ducts (not shown) into the suction fan (not shown) and thence into the outside atmosphere, thereby forming a bat of fibers on the drum exterior surface. Baffle 58 seals off the air suction from the lower part of drum 56. Roll 59 assists in forming the fibrous bat against the condenser drum. Doffer cylinder 60 is rotatably mounted and positively driven in the direction shown. Any conventional driving means may be used for this purpose. Each toothed disc 61, set very close to drum 56, will positively remove all fibers from the drum, and by means of centrifugal action will throw these fibers into any desired container 62 or duct.

Another application of the invention is to a conventional saw type cotton gin, the action of which is too well known to require a detailed description. Our doffer may be used to remove the cotton fibers from the saw teeth in a manner already described in connection with the previously cited embodiments illustrated in Figs. 1-3.

We claim:

In a fiber processing machine having a rotatable processing cylinder which collects fibers on its periphery during their processing, a doffer for removing the fibers from the processing cylinder, 70 said doffer comprising a rotatable doffer cylinder with its axis parallel to that of the processing cylinder and provided with radially extending doffer teeth on its periphery running closely adjacent to, but out of contact with, the periphery of the processing cylinder, the forward edge of each of

said doffer teeth being constructed at such an angle to the radius of the doffer cylinder that the doffer teeth collect the fibers from the periphery of the processing cylinder as they run closely adjacent thereto, and the fibers are expelled therefrom by centrifugal force within a complete revolution of the doffer cylinder.
